CLAIM

The ornamental design for a shower enclosure, as shown and described.

DESCRIPTION

FIG. 1 is a sectional view of a shower enclosure embodying my new design taken on line 1—1 of FIG. 5; FIG. 2 is a perspective view taken from the top, front and right side thereof;

FIG. 3 is a front plan view thereof;

FIG. 4 is a cross-sectional view taken on line 4—4 of FIG. 5;

FIG. 5 is a cross-sectional view taken on line 5—5 of FIG. 1; and,

FIG. 6 is a perspective view showing a shower enclosure embodying my new design mounted in typical fashion through a wall.

The fragmentary broken line representations of a floor in FIG. 2 and of a wall in FIG. 6 are for the purpose of illustration only and form no part of the claimed design.

FIG. 1.

FIG. 3.

FIG. 2.

FIG. 4.
